CLAIM

The ornamental design for a power adapter, substantially as shown and described.

DESCRIPTION

FIG. 1 is a front, top perspective view of a power adapter comprising an embodiment of a new, original and ornamental design;

FIG. 2 is a front view thereof;

FIG. 3 is a back view thereof;

FIG. 4 is a left-hand side view thereof;

FIG. 5 is a right-hand side view thereof;

FIG. 6 is a top view thereof;

FIG. 7 is a bottom view thereof; and,

FIG. 8 is a back, bottom perspective view thereof.

The broken line portions of the figure drawings are included to show unclaimed subject matter only and form no part of the claimed design.

1 Claim, 4 Drawing Sheets
